VEHICLE CLEANING APPARATUS

Earl Dallas Smith, 6202 E. Sage Drive, Scottsdale,
Ariz. 85251, and Dale R. Oldham, 7028 N. 11th
St., Phoenix, Ariz. 85020

Filed Dec. 18, 1967, Ser. No. 9,820

Term of patent 14 years

Int. Cl. D15—06

U.S. Cl. D49—12

Fig. 1

Fig. 2

Fig. 3.

FIG. 1 is a perspective view of vehicle cleaning apparatus showing our new design as it appears when viewed from above and to the right of the point of entrance of the vehicle thereto.

FIG. 2 is a perspective view thereof seen from above and to the side of the exit end.

FIG. 3 is a top plan view thereof.

Dominant features of our design reside in portions shown in full line.

We claim:

The ornamental design for a vehicle cleaning apparatus, substantially as shown and described.
